UNITED STATES PATENT OFFICE.

WILLIAM B. JOHNSON, OF ROCKFORD, ILLINOIS, ASSIGNOR TO ROCKFORD MACHINE & SHUTTLE COMPANY, OF ROCKFORD, ILLINOIS, A CORPORATION OF ILLINOIS.

HEMSTITCHING ATTACHMENT FOR SEWING-MACHINES.

No. 918,750.

Specification of Letters Patent.

Patented April 20, 1909.

Application filed March 16, 1908. Serial No. 421,341.

To all whom it may concern:

Be it known that I, WILLIAM B. JOHNSON, a citizen of the United States, residing at Rockford, in the county of Winnebago and State of Illinois, have invented certain new and useful Improvements in Hemstitching Attachments for Sewing-Machines, of which the following is a specification.

The object of this invention is to provide an attachment for sewing machines for producing hemstitching.

My invention consists of a rotatable plate provided with a series of needle openings, any one of which can be brought into alignment with the needle, the thickness of the plate varying with each of the openings will produce hemstitching of various widths.

The further object of this invention is to form the needle opening in an inclined surface in order that the stitch will more readily free itself from the attachment.

In the accompanying drawings, Figure 1 is a perspective view of the attachment showing the location of the finger. Fig. 2 is a perspective view of the attachment in which the finger is broken away to more clearly show the rotatable plate. Fig. 3 is a vertical section through the rotatable plate and support for the plate.

The attachment comprises the edge section 1 which is provided in this instance, with the hooks 2 which are adapted to engage the presser foot bar of a sewing machine, and clamped thereto in any suitable manner.

Other forms of connection of the attachment with the presser foot may be devised, and may vary with the different styles of sewing machines. From the edge section 1 depends a foot section 3 which is adapted to take the place of the foot of a sewing machine attachment. The other end of this edge section 1 has a bar 4 extending at right angles thereto, and from the bar 4 extends an arm 5, the free end of which has an enlargement 6. Over the enlargement 6 is located a rotatable plate 7 and is connected therewith by the screw 8. This plate is square in outline and has its upper surface formed with the four bevels 9, 10, 11 and 12.

The bevels starting from the top 13 of the plate and tapering toward the edges of the plate. The bevel 9 comes to a sharp edge 14; the bevel 12 having the thickest edge 15,

and the bevels 10 and 11 having edges 16 and 17 respectively of thicknesses varying between the edges 14 and 15. The bevels 9, 10, 11 and 12, each have a needle opening and slots 18, 19, 20 and 21 respectively, the slots extending from the openings out through the edge of the bevel.

The enlargement 6 has a needle opening 22 and a slot 23 extending from the opening out through the edge 24, of the enlargement. The opening and slot of the enlargement coinciding with the opening and slot of the rotatable plate when the plate is in working position. From the upper face of the enlargement extends a stud 25, which is located to receive the needle opening of the bevel of the rotatable plate opposite the needle opening 22 of the enlargement 6. This pin holds the rotatable plate from rotation.

To the end of the bar 4 is pivoted a finger 26 which extends over the center of the rotatable plate, and from the finger depends a stop 27 which engages the edge of the arm 5, and limits the movement of the finger and locates it properly over the rotatable plate.

In use the attachment is secured to the presser bar of a sewing machine which will locate the foot section 3 over the cloth feeder of the machine, and the needle opening 22 in the enlargement will permit the needle to move vertically through it. The finger 26 is moved on its pivot to expose the rotatable plate 7. A strip of cloth 28 is placed over the rotatable plate and another strip of cloth 29 is placed beneath the enlargement 6 and both located between the foot section 3 and a cloth feeder. The foot section 3 is then lowered onto the cloth feeder, the sewing machine is set in motion which will feed both strips of cloth together, and the needle will move through the opening of one of the bevels and through the opening 22 in the enlargement 26. The thickness of the enlargement and of the bevel will determine the width of the hemstitching. By the employment of the bevels, the stitches are easily shed.

By adjusting the rotatable plate to bring other of the needle openings to coincide with the needle opening in the enlargement 6, a greater thickness of the plate will be

had which will increase the width of the hemstitching.

I claim as my invention.

1. A hemstitching attachment comprising a support adapted to be connected to the presser bar of a sewing machine, and a rotatable plate adjustably connected with the support, the plate having a plurality of beveled sections, each section having a needle opening and a slot communicating with the opening and extending through the edges of the section.
2. A hemstitching attachment comprising a support adapted to be connected to the presser bar of a sewing machine, and a rotatable plate adjustably connected with the support and having a plurality of beveled sections, each section having a needle opening, and a slot communicating with the opening and extending through the edges

of the plate, the edges of the beveled sections being of varying thicknesses.

3. A hemstitching attachment comprising a support adapted to be connected to the presser bar of a sewing machine, a rotatable plate adjustably connected with the support, the plate having a plurality of beveled sections, each section having a needle opening and a slot communicating with the opening and extending through the edges of the sections, and a movable finger having one end located over the pivot of the plate.

In testimony whereof I have hereunto set my hand in presence of two subscribing witnesses.

WILLIAM B. JOHNSON.
